INTERNAL COMBUSTION ENGINE

Original application filed November 4, 1927, Serial No. 231,025. Divided and this application filed January 17, 1930. Serial No. 421,890.

This invention relates to internal combustion engines and more particularly to that type of engine in which a rotating valve is employed for the purpose of controlling the inlet and exhaust of each combustion chamber thereof. The invention more particularly pertains to valve actuating means, as will appear; and this application is a division of my copending application Serial No. 231,025, filed November 4, 1927, to which reference may be had for details generally indicated but not specifically set forth herein.

Accessibility of parts is of well-known importance, and an object of my invention is to so arrange the parts that access may be had to the same for inspection or removal and replacement with a minimum of effort and with least disturbance of other parts.

A more commercial difficulty encountered in designing a rotary valve of individual type is that of accurately timing the several valves in their respective cylinders, and a purpose of my design is that the valves be capable of being timed with a minimum of effort and chance of error.

Where the sleeve type of valve is employed, in which the piston is arranged to move, an objection is usually that an additional spacing of cylinders on the crankshaft center line is necessary, owing to the dimensions of the sleeves themselves or of their driving means. An object of the present invention is to arrange the driving mechanism for a sleeve type of valve whereby the additional spacing required is a minimum.

The exact nature of this invention together with further objects and advantages thereof will be apparent from the following description taken in connection with the accompanying drawings in which Fig. 1 is a typical transverse section in elevation of an engine in which are embodied the various features of my invention; Fig. 2 is a horizontal section as in the plane of line 2—2, Fig. 1; Fig. 3 is a horizontal section in the plane of line 3—3, Fig. 1 (also Fig. 4), the section including a number of cylinders of the engine; and Fig. 4 is a detail in vertical section as in the plane of line 4—4, Fig. 3 and generally corresponding to the showing of Fig. 1.

The principal parts of the engine chosen for illustration of my invention, and their arrangement, are generally similar to what is at present standard practice in the internal combustion art with reference to operation on a four-stroke cycle, these parts comprising a cylinder block casting 1 mounted upon a crank case 2 in which is a crank shaft 3, upon each crank 4 of which bears the lower end of a connecting rod 5 having connection through a wrist pin 6 with a piston 7 in the corresponding cylinder.

The cylinder block 1 is bored out to form a number of aligned "cylinders" 8, each cylinder being open at its top or head end and having a cooling water space 9 thereabout formed by a jacket wall portion 10 which extends around the block. Adjacent the head end on one side of the common diametrical plane of the cylinders, each cylinder is provided with a number of longitudinally elongated ports 11, 12, 13, 14, as indicated particularly in Fig. 2. In the cylinder block and extending between the lateral face 19 thereof and the several cylinder ports are a number of passages appearing in Fig. 2 and bearing reference numerals 15 to 18 therein. The ports 12 and 14 through the passages 16 and 18 are adapted for connection as through a manifold, not shown, with the usual carburetor; and the ports 11 and 13 similarly through the passages 15 and 17 are adapted for connection with a suitable exhaust manifold. In each cylinder is arranged a valve 20 which may be of the sleeve type indicated, the piston being arranged for reciprocating movement therein. Each valve 20 is provided with a number of ports, three, 21, 22, 23, being shown, equally spaced about and adjacent the head end thereof at elevation corresponding to that of the cylinder ports. The spacing of each series or pair of cylinder ports corresponds with the spacing of the valve ports whereby, for example, the two inlet ports 12 and 14, shown, of each cylinder, will be opened and closed simultaneously by adjacent valve ports.

The valves are arranged for rotation in a manner to be described, in the direction of the arrows, Fig. 3, and the cylinder ports are

properly located in their cylinders whereby the inlet ports and exhaust ports of each cylinder will be opened and closed in proper timed relation with the motion of the corresponding piston therein, whereby the cylinder may operate on the well-known four-stroke cycle; and the timing or relative angular setting of the valves is such that a proper firing sequence will be had in the several cylinders, as will be well understood by one familiar with the art.

Each cylinder is provided at its head end with a closure member or so-called cylinder head 25 which may be conveniently a single casting as indicated, Fig. 2, having a flange portion 26 secured as by bolts 34 on the gasket 27 on the top face of the cylinder block about the periphery of the cylinder bore. Each cylinder head has an opening properly threaded for reception of spark plug 29. A jacket head 32 extends along the top of the cylinder block seating upon the outer extremities of the gasket 27 overlying the jacket wall portions 10 and having openings arranged to receive the upwardly extending portions 30 of the several cylinder heads.

Each cylinder head 25 has a depending portion 35 extending downwards within the cylinder and the valve therein and terminating in a transverse face 36 just clearing the head of the cylinder at its upper dead center and therefore lying in a plane just slightly above that of the lower edges of the cylinder ports. Each cylinder head is cut away adjacent the cylinder port area so that the depending portion 35 thereof is offset with respect to its cylinder axis, the longitudinal face 37 of each depending portion having the curvature indicated in the drawings, and terminating adjacent the outer vertical edges of the outer cylinder ports 14 and 22; and the depending portion 35 serving to mask that portion of the head end of the valve not overlying the cylinder port area. That portion of the cylinder head extending within the cylinder is finished off cylindrically to just clear the valve without contact therewith. The depending portion of each head is hollow, as indicated, and open at the top for free communication with the cooling medium within the water jacket.

The upper face of the crank case 2 is finished off as usual and the lower cylinder block face similarly finished whereby a firm seat may be had between the two parts. The crank case is provided as usual with openings 38 aligned one with each cylinder for connecting rod clearance. Overlying and secured with the crank case and surrounding each opening 38 is a bearing washer or bushing 39. Seated upon each bushing 39 is a ring gear 40 counter-bored out as indicated to form a flange 43 and to receive the lower extremity of the valve 20, and seating upon the bushing throughout the full bearing sur-

face thereof; the cylinder block being cut away as indicated to provide clearance above and about the ring gear. The lower periphery of the valve is provided with a number of notches 41 preferably equal in number and aligned respectively with the valve ports. The ring gear 40 has corresponding inwardly projecting lugs 42 engaging the notches 41 but of inwardly extending dimension to underlie the inner surface of the valve. The notches 41 are of greater longitudinal dimension than are the lugs 42. Between the lower extremity of the valve and therefore in supporting relation therewith and overlying the flange 43 of the ring gear is a spring 44. A similar spring may be positioned about the upper extremity of the valve bearing against the flange 26 of the cylinder head, sufficient clearance being provided for the purpose.

The cylinders in the block 1 are spaced in pairs whereby each is closer to one of its adjacent cylinders than to the other, and this spacing is such that the teeth 46 of alternate adjacent pairs of gears will mesh with each other whereby, as indicated in Fig. 3, the teeth of each gear will mesh with those of the gear of one adjacent cylinder but will clear those of the gear of the other adjacent cylinder.

The lower extremity of the cylinder block 1 is secured with the crank case by a number of bolts 47 and 48. About the bolts 47, which lie between the most widely spaced pairs of cylinders, are spacer lugs 49 preferably integral with the cylinder block and terminating downwardly with faces finished flush with that surface of the cylinder block which bears upon the crank case. One side of the cylinder block in the plane of the gears 40 has an opening 50 provided with a suitable cover 51. No spacer lugs are provided adjacent the bolts 48 for a reason which will later appear.

Opposite the opening 50 and extending along the cylinder block in suitable bearings 56 therein is a shaft 52 driven by the engine crank shaft through any suitable connection such as the sprockets 53 and 54 and chain 55 appearing in Fig. 1, whereby the shaft 52 is rotated in a counter-clockwise direction, Figs. 1 and 4, in timed relation with the engine shaft, and in the engine illustrated at a speed two-third revolutions to every one revolution of the crankshaft. On the shaft 52 opposite each ring gear 40 is a pinion 57 having teeth meshing with those of its ring gear. The teeth of the gears and pinions are helically arranged thereon, and in the example chosen for illustration, the tooth angle is 45° and the pitch diameters of the ring gears are four times the pitch diameters of the pinions, whereby the ring gears will be rotated at one-sixth crank shaft speed.

Each pinion 57 has a hub portion 58. Each

pinion with its hub portion is bored to freely fit upon the shaft 52, and the hub portions are transversely slotted as at 59. The shaft 52 is provided between each pair of bearings 56 with a pair of keyways 60 spaced at 180° and extending between and somewhat beyond the center lines of those most closely spaced pairs of ring gears. In the keyways 60 are keys 61 notched at their ends, as indicated, to form shoulders 62. The clearance between the shoulders 62 on each of the keys 61 is such that when the pinions 57 are placed in abutting relation therewith, the pinions will be in spaced relation as are their ring gears as shown in Fig. 3; and the arrangement is such that the pinions may slide but not rotate on the shaft.

Operation of the engine is as follows: The engine is arranged for operation of the crank-
20 shaft in a counter-clockwise direction, Fig. 1, and the timing of the valves, of course, is such that a four stroke cycle of operations will be repeatedly effected in each cylinder. In detail, assuming the piston of any cylinder
25 at the top of its stroke, as rotation of the crankshaft causes downward motion of the piston, the valve is rotated to open the intake ports 12 and 14 so that a charge of combustible mixture may be induced by suction into
30 the cylinder. During the succeeding upward stroke of the piston the valve progresses to close all of the ports so that the contents of the cylinder are compressed. As the piston attains the top of its stroke, a spark is ef-
35 fected at the electrodes 63 of the spark plug 29 in the usual manner. The contents of the combustion chamber are ignited, and immediately expand to force the piston downwards with great power. As the piston
40 reaches the bottom of its stroke the valve progresses in its travel sufficiently to open the exhaust ports 11 and 14 which remain open throughout the next succeeding upward stroke of the piston, whereby the products
45 of combustion are forced out of the cylinder.

By the provision of the springs 44 and 45, and the engaging means between the valve and the ring gear already described, while
50 rotational movement of the valve is posi-
tively effected by its ring gear, a limited spring-opposed longitudinal motion is al-
lowed the valve. It is possible that the valve may hence somewhat follow the motion of
55 the piston; but, at least at the time of igni-
tion, the valve being unbalanced as to pres-
sure, will move downwardly to compress the lower spring 44 to a maximum, return or up-
ward motion of the valve occurring with suf-
60 ficient pressure drop in the cylinder and be-
ing yieldingly limited by the upper spring
45, the effect of the lower spring 44 upon the valve being limited by the lugs 42 described.

This slight longitudinal valve movement is
65 sufficient to prevent the cutting of the valve

in the cylinder walls which would otherwise occur.

By the arrangement of pinion drive de-
scribed, the thrust of the ring gears will be
against the bushings 39, and those pinions
meshing with intermeshing pairs of ring
gears are maintained in spaced relation, free
of longitudinal movement as a unit on the
shaft 52, and positively rotated by the shaft
52. The result of intermeshing the ring gears
is that the cylinder spacing may be decreased,
and the result of the pinion arrangement is
that each pair of pinions may find its own
center with respect to the ring gears driven
thereby, so that tooth load upon the ring
gears and pinions is effectively equalized. A
further and important advantage, is that
where resistance to rotation of one valve be-
comes greater than the resistance of the other
valve of the pair, as during the combustion
period in one cylinder occurring simultane-
ously with, say, the exhaust or suction period
of the other cylinder, the pinion unit may
slightly shift longitudinally upon the shaft
52 and allow the ring gear of the valve hav-
ing the lightest load to transmit some of the
power to the ring gear of the more heavily
loaded valve. Thus, at such periods, the
tooth load on the ring gear of the most heavily
loaded valve is reduced one half.

Preferably, the number of teeth on each
ring gear is a multiple of the number of ports
in the valve, and preferably, the notches 41
are aligned with the valve ports. By this ar-
rangement, timing of the valves is a relatively
simple matter and requires merely proper
timing of the ring gears relative to their pin-
ions. This is easily accomplished by employ-
ing the lugs 42 as indices, each ring gear being
first placed in proper engaging relation with
its pinion, whereupon engagement of the
valve with its ring gear in any possible position
will result in proper timing of the valve.

By the arrangement described, removal of
any part of any cylinder assembly may be
easily effected as follows, assuming the water
jacket head portion 32 removed. By re-
moval of the usual cylinder head bolts, the
cylinder head 25 may be withdrawn. The
valve may be thereupon freely lifted out of
the cylinder; or if it is merely desired to re-
move the ring gear thereof, assuming the
cover 51 and outer bolt 48 removed, the valve
is simply raised sufficiently to clear the ring
gear, whereupon the same may be laterally
slid upon the bushing 39 and rolled upon the
opposite ring gear of its pair out through the
opening 50. The bushing 39 may then be
easily removed from its seat. Removal of
the ring gears allows free access for inspec-
tion of the pinions. Disassembly of the pin-
ions 57 from the shaft 52 for removal of the
shaft 52 may be effected by sliding apart
each pair of pinions (accompanied by corre-
sponding movement of the ring gears if still
125

in position), and removal of the interlying keys 61, whereupon the shaft may be slid longitudinally out of the cylinder block and the pinions slid off the shaft at the same time.

5. What I claim is:

1. In an internal combustion engine having a ported cylinder, a sleeve valve arranged for control of the cylinder ports, and a valve actuating member positioned about and in driving relation with said valve, said cylinder having a lateral opening adapted to allow removal of said actuating member dependent upon disconnection of said valve therefrom.
15. 2. In an internal combustion engine having a ported cylinder, a sleeve valve arranged for control of the cylinder ports, and a valve actuating member positioned about and in driving relation with said valve, and disconnectible therefrom by longitudinal movement of the valve in the cylinder, a head for said cylinder removable therefrom to allow the valve said disconnecting movement, said cylinder having a lateral opening adapted to allow removal of said actuating member upon disconnection of said valve therefrom.
25. 3. In an internal combustion engine having a ported cylinder, a sleeve valve arranged to control the ports thereof, a ring gear positioned about and in driving relation with said valve, and a pinion in driving relation with said gear, said cylinder having a lateral opening opposite said pinion and adapted to allow removal of said ring gear therethrough without affecting said pinion.
35. 4. In an internal combustion engine having a ported cylinder, a crankcase, a sleeve valve arranged in said cylinder to control the ports thereof and extending beyond said cylinder, a ring gear positioned about said extending valve portion and in driving relation therewith, a pinion in driving relation with said gear, said cylinder having a lateral opening opposite said pinion and adapted to allow removal of said ring gear, and means securing together cylinder and crankcase portions adjacent said opening and obstructing said opening and being removable to allow said ring gear removal.
45. 5. In an internal combustion engine having a pair of ported cylinders, a sleeve valve in each of said cylinders arranged to control the ports thereof, a gear for driving each of said valves, said gears intermeshing, a driving shaft, a pair of pinions slideable and non-rotatably mounted on said shaft and meshing one with each of said gears, and means for controlling the spacing apart of said pinions.
55. 6. In an internal combustion engine having a ported cylinder, a valve arranged for rotary movement in said cylinder to control the cylinder ports and having a plurality of ports equally spaced thereabout, a driv-

ing member for said valve, said valve and driving member having interengaging portions adapted to effect driving connection of said valve and driving member in any relative position thereof in which said valve is properly timed.

In testimony whereof I hereby affix my signature.

FRANK R. HIGLEY.
